UNITED STATES PATENT OFFICE.

CLETUS A. BROWN, OF STUTTGART, ARKANSAS.

TRACTOR.

1,178,838.

Specification of Letters Patent. Patented Apr. 11, 1916.

Application filed March 27, 1914. Serial No. 827,698.

To all whom it may concern:

Be it known that I, CLETUS A. BROWN, a citizen of the United States, residing at Stuttgart, in the county of Arkansas and State of Arkansas, have invented new and useful Improvements in Tractors, of which the following is a specification.

This invention relates to tractors or traction engines of the type driven by an internal combustion engine and designed especially for farm use in hauling or pushing various implements and driving machines and implements of various kinds, the primary object of the invention being to provide a traction motor which is strong, durable, and comparatively inexpensive of construction, adapted to be readily and conveniently controlled and handled and operated for driving stationary or traveling implements, and which is capable of traveling over rough and soft ground without liability of injury.

A further object of the invention is to provide a traction motor which may be driven forward or backwardly at will, easily and conveniently steered over all kinds of ground, and in which the construction of the frame work and gearing is such as to adapt the traction motor for rough usage without liability of damage to or derangement of the working parts.

A still further object of the invention is to provide a traction motor which, while of maximum strength and durability, is comparatively light in weight and designed to furnish a maximum amount of driving power.

The invention consists of the features of construction, combination and arrangement of parts herein fully described and claimed, reference being had to the accompanying drawings in which:

Figure 1 is a side elevation showing the traction motor, as used in connection with a binder for traction and driving purposes. Fig. 2 is a top plan view of the same, showing portions of the binder in section. Figs. 3 and 4 are front and rear elevations, respectively, of the traction motor. Fig. 5 is a bottom plan view of the same. Figs. 6 and 7 are vertical transverse sections on the lines 6—6 and 7—7 of Fig. 2. Fig. 8 is a vertical longitudinal section through the machine. Fig. 9 is a sectional plan view with the motor and its bent frame removed. Fig. 10 is a

perspective view showing generally the axle and frame work construction.

In carrying my invention into practice, I provide a tractor 1 having a transmission shaft 2 provided with a coupling portion 3 connected therewith by a universal joint 4. This transmission shaft is adapted for connection with a drive shaft upon a binder or other implement A, the tongue B of which may be suitably constructed to engage a draft clevis or connection 5 on the rear axle frame of the tractor. The implement A may thereby be connected with the tractor so as to be drawn or pushed by the latter across a field or along a roadway. The drive shaft C on the binder or implement is provided, as shown, with a coupling portion C' connected therewith by a universal joint C², so that the coupled transmission and driving shafts upon the tractor and implement will have a wide range of flexibility to permit the coupled portions to work at different angles in the travel of the combined apparatus. The portions 3 and C' preferably have a telescopic connection to compensate for variations in the distance between the tractor and implement. The tractor includes front and rear axles 6 and 7 connected by a reach bar 8, each of said axles comprising an upper straight horizontal plate 9 and a lower horizontal plate 10, having bent end portions 11, the straight end portions of the plate 9 and bent end portions of the plate 10 forming bearings for vertical shafts 12 upon which are mounted steering knuckles 13, carrying spindles 14, supporting and steering wheels 15 being journaled on the knuckled spindles of the front axle and similar wheels 16 upon the knuckled spindles of the rear axle, which wheels have broad concaved treads for a firm bearing upon and tractive engagement with the ground. As shown, the sets of knuckles are provided with front and rear crank arms 17 and 18 coupled by connecting rods 19 and 20, each pair of connecting rods forming parallel motion links, whereby the associated wheels are adapted to swing laterally in unison for steering action.

Journalized upon the upper ends of the knuckle shafts are double beveled gears 21 which mesh with gears 22 fixed to the hubs of the coacting wheels and also with beveled gears 23 on a transverse transmission shaft, the front and rear transmission shafts being

denoted 24 and 25, respectively. Each of said transverse shafts is journaled in bearings 26 rigidly fastened to the plates 9 and 10 of the associated axle, which bearings are provided with lateral supporting lugs or flanges 27, for a purpose hereinafter described. The two axles are connected by the reach bar or plate 8, which is comparatively broad or wide except at its forward end, which is reduced to provide a spindle 29 journaled in the arms of a bracket yoke 30 secured to the front axle, by which the front and rear axles, and the parts of the tractor respectively mounted thereon, and respectively constituting two sections of the tractor, are swiveled for relative pivotal motion in a vertical plane, so that the ground wheels may ride over varying irregularities of ground surface without liability of injury to the parts of the tractor.

The connecting rod 20 of the front steering gear and connecting rod 19 of the rear steering gear are coupled by links 31 and 32 to bell crank levers 33 and 34 supported by the body portion of the reach bar, said levers being connected for movement in unison by a link 35 and the rear bell crank lever being mounted on a vertical shaft 36 suitably journaled upon the reach bar and provided with a control wheel 37, whereby the two sets of wheels may be simultaneously adjusted for a turning motion of the tractor within short radius.

A driving motor 38, preferably of the gasoléne type, is mounted upon a bed or supporting frame composed of longitudinal bars 39 connected by cross bars 40, the rear ends of which bars diverge and are arranged to rest upon the lugs or flanges 27 of the sets of the bearings 26, supported by the rear axle, by which said motor bed or frame is rigidly mounted at its rear end upon the axle. The forward ends of the bars 39 rest upon similar lugs or flanges 41 formed upon a bearing 42 arranged in advance of a bearing 43, said bearings being formed upon or rigidly fixed to the broad portion of the reach bar. The bearings 42 and 43 support a longitudinally extending countershaft 44, which is driven from the motor in either direction in a manner hereinafter described, and which is coupled at its forward end by a universal joint 45 with a shaft 46 journaled in the bracket yoke 30, which shaft 46 carries a beveled gear 47 meshing with a beveled gear 48, whereby the front transverse shaft 24 is driven from the motor to communicate driving motion to the front wheel 15.

60 The joint 45 has an extensible or telescopic connection with the shaft 46 by which the shaft is adapted to lengthen and shorten, to compensate and provide for a proper relative motion of the parts.

65 The shaft 46 is provided at a point be-

tween the journal portion or body of the shaft and the joint 45 with a second joint 45', also of the universal type, whereby the range of flexibility of the free end of said shaft is increased.

The rear end of the shaft 44 carries a beveled gear 49, which meshes with a gear 50 on the rear transverse shaft 25, by which the rear wheels 16 are positively driven. The shaft 44 further carries a gear 51 and a gear 52, the gear 51 being arranged to mesh directly with a drive gear 53 on the motor shaft 38', while the gear 52 is adapted to mesh with an idle gear 54 journaled on the engine bed or frame, which in turn meshes with a second drive gear 55 on the engine shaft, whereby motion may be imparted from the engine shaft to the countershaft through two different sets of gears for driving the tractor either forwardly or backwardly. A suitable sleeve and shifter lever 56 and 57, respectively, are provided whereby the gears 51 and 52 may be alternatively thrown into and out of operation. A sprocket wheel 58 is also mounted on the engine shaft and is connected by a chain 59 with a sprocket wheel 60 on the transmission shaft 2, which is journaled in a bearing yoke 61 supported by a reach bar and rear axle.

A clutch device 62 is provided whereby the sprocket wheel 58 may be thrown into and out of action at will so as to start or stop the motion of the transmission shaft, it being understood, from the foregoing description of the gearing between the motor shaft and countershaft and motor shaft and transmission shaft that the countershaft may be driven backwardly and forwardly from the motor at will while the transmission shaft is running or at a state of rest. Suitable braces 63 may be provided for reinforcing the reach bar from the rear axle, and the bent portions 11 of the lower plates 10 of each axle may be connected and reinforced by a truss rod 64.

It will be observed that the forward end of the motor frame is arranged to overhang the universal joint connection 45 between the countershaft 44 and shaft 46, allowing free clearance for the motion of the parts of the joint, as well as free easy motion of the front and rear sections of the tractor on the swivel connection between the reach spindle and front axle. It will also be observed that the construction described provides a tractor which, while strong and durable in construction, may be made light in weight, so that it may be driven and steered with great facility over even very rough surfaces. Inasmuch as free relative motion between the front and rear sections of the tractor is permitted, it will be understood that the tractor may be accommodated itself to varying irregularities of

ground surface without transmitting jolts or jars to the gearing, and that by means of the latter the tractor may be positively driven in either direction and the transmission shaft operated at the same time for the purpose of communicating power to any type of farm apparatus or implement.

While I have in the present instance, for purposes of illustration, shown the tractor 10 as arranged for pulling a binder and simultaneously driving the working parts thereof, it will be understood that the tractor may be employed for pulling or pushing any other type of traveling farm implement and 15 simultaneously operating the parts thereof, and that the tractor may also be employed to furnish power for driving all kinds of stationary farm or other machinery.

20 I claim:—

1. A traction motor comprising a frame structure including an axle and a reach, a yoke upon the axle, a spindle upon the reach 25 journaled in said yoke, vertical shafts journaled upon the axle and provided with spindles and steering knuckles, steering gear connected with said knuckles, ground wheels journaled on the spindle, gears loose on the 30 vertical shafts and meshing with the aforesaid gears, a transverse shaft in gear with the loose gears, a longitudinally extending drive shaft, a motor for driving said shaft, a longitudinally extending driven shaft 35 journaled upon the axle and yoke, a gear upon said shaft meshing with the gear upon the transverse shaft, and a universal joint connection between said driven shaft and the driving shaft.

40 2. A traction motor comprising a frame structure including an axle, vertical shafts journaled upon the axle and provided with

spindles and steering knuckles, steering gear connected with said knuckles, ground wheels journaled on the spindles, gears loose on the vertical shafts and meshing with the 45 aforesaid gears, a transverse shaft in gear with the loose gears, a drive shaft in gear with said transverse shaft, a motor, a transmission shaft, direct and indirect gearing between the motor and drive shaft, means 50 for adjusting said gearing to throw the same into and out of operation or for connecting the driving shaft with the motor for backward or forward propulsion, a transmission shaft in gear with the motor and 55 means for throwing the same into and out of operation.

3. A traction motor including a frame structure and an axle, a longitudinally extending drive shaft, a driven shaft flexibly connected with the drive shaft, a transverse shaft driven by said driven shaft, wheels in gear with said transverse shaft, a motor having its shaft parallel with the driving shaft, a second transverse shaft in gear with the drive shaft, wheels driven from second transverse shaft, variable speed gearing between the motor shaft and drive shaft, 60 means for adjusting said gearing, said variable speed gearing embodying forward 65 and reversing drive gearing, a transmission shaft, gearing between said transmission shaft and the motor shaft, and means for throwing said gearing into and out of 70 action.

In testimony whereof I affix my signature in presence of two witnesses.
